MASSAGER

Julian R. Haynes, Hinsdale, Ill., assignor to Sunbeam Corporation, Chicago, Ill., a corporation of Illinois

Filed June 7, 1968, Ser. No. 12,263

Term of patent 14 years

Int. Cl. D24—02

U.S. Cl. D83—1

FIG. 1 is a perspective view of a massager embodying my new design;

FIG. 2 is a side elevational view thereof;

FIGS. 3 and 4 are rear and front elevational views, respectively, thereof;

FIG. 5 is a top plan view thereof; and

FIG. 6 is a bottom plan view thereof taken on line 6-6 of FIG. 2 with portions partially in section.

The dominant features of my design reside in those portions shown in full lines.

I claim:

The ornamental design for a massager, as shown and described.
